US00D819042S

(12) **United States Design Patent** (10) **Patent No.:** **US D819,042 S**
Ebler et al. (45) **Date of Patent:** **** May 29, 2018**

(54) **DISPLAY SCREEN OR PORTION THEREOF WITH GRAPHICAL USER INTERFACE FOR A MEDICAL DEVICE**

(71) Applicant: **MAQUET Cardiopulmonary GmbH**, Rastatt (DE)

(72) Inventors: **Ralph J. Ebler**, Warwick, NY (US); **Daniel Medart**, Hillsdale, NJ (US)

(73) Assignee: **MAQUET CARDIOPULMONARY GmbH**, Rastatt (DE)

(**) Term: **15 Years**

(21) Appl. No.: **29/541,759**

(22) Filed: **Oct. 7, 2015**

(51) LOC (11) Cl. **14-04**

(52) U.S. Cl. **D14/485**
USPC ....

(58) **Field of Classification Search**

USPC D14/485-488, 490, 494, 489, 491-493,
D14/495

CPC . G06F 3/0482; G06F 3/04842; G06F 3/04817

(57) **CLAIM**

The ornamental design for a display screen or portion thereof with graphical user interface for a medical device, as shown and described.

DESCRIPTION

The FIGURE is a front view of a display screen or portion thereof with graphical user interface for a medical device. The broken lines showing portions of the graphical user interface and the display screen form no part of the claimed design.

1 Claim, 1 Drawing Sheet
